CLAMP

John M. Mikoski, Spokane, Wash.

Application June 5, 1952, Serial No. 291,885

1 Claim. (Cl. 24—262)

1

This invention is an improved clamp and one object of the invention lies in the provision of a clamp which is quickly and easily applied with the jaws in selective spaced relation.

Another object of the invention lies in the provision of spaced clamps adapted to secure the bottom rail of a Venetian blind in spaced parallel relation to the sill of a window while the tapes are drying after laundering, for the purpose of eliminating shrinkage.

Another object of the invention lies in the provision of a clamp having pads for precluding marring of the elements clamped thereby.

Another object of the invention lies in the provision of a clamp having cooperating teeth for adjustably securing the jaws at selective spaced positions.

Another object of the invention lies in the provision of a clamp having novel means for releasably holding the teeth in cooperating relationship.

Another object of the invention lies in the provision of a clamp which is very inexpensive to manufacture of a minimum number of parts which are not liable to get out of working condition.

These and other objects of the invention will become apparent to the reader during the course of the following description.

In the accompanying drawings, forming a part of this specification, and in which like numerals are employed to designate like parts,

Figure 1 is an elevational view of a window having a Venetian blind and showing the invention in use,

Figure 2 is a fragmentary cross section of a portion of the window, blind and my improved clamp,

Figure 3 is a perspective view of the preferred form of my invention,

Figure 4 is a fragmentary elevation of a modified part of the improved clamp, and,

Figure 5 is a side elevation of a further modified clamp.

Referring now more particularly to the drawing, I have shown a window W having a sill S and a Venetian blind B pivotally supported at the top within the window W and having multiple horizontal and vertically spaced slats M carried adjacent each end by means of tapes T usually formed from cotton webbing and having cross supports C. A horizontal rail R is provided at the bottom of the blind and is axially movable by the tapes to facilitate proper tilting of the slats for the blinding effect.

2

Because of the multiplicity of the slats and their close proximity to each other, it is very difficult to clean the blinds. Therefore, many people remove the blinds and place them in the bath tub or a similar container where they can wash them with a considerable amount of water and soap or detergent, and then after a superficial drying, to eliminate dripping water, the blinds are re-hung and left to dry.

It has been found that as the tapes dry, they shrink and thus cause the blind to become too short for the window and partially ineffective as a blind as well as unsightly.

In an effort to overcome this, I have seen women drive nails in the window casings or hang weights from the rail R to prevent shrinkage. These methods obviously are objectionable because they mar the woodwork and walls and permit the tapes to dry at uneven lengths, tending to render the blind unsightly by reason of its hanging crooked.

The present invention therefore, was developed and has been found very effective, inexpensive and useful for this purpose. It is not my intention, however, to limit the scope of my invention unnecessarily and therefore desire to broadly claim the invention as limited only by the appended claim in view of the prior art.

The improved clamp 10 has a pair of cooperating spaced parallel jaws 11 which are adapted to clamp the "work" therebetween. Felt facings 12 are secured to the inner jaw faces 13 to preclude marring the finish of the work clamped.

Each jaw is provided at its rear end with a leg 14 and one leg differs from the other. The depending leg of the upper jaw 11 has a body 15 formed straight throughout its length and is secured to the jaw by means of a short radius bend 16 disposing the leg at right angle to the jaw 11. A major portion of the inside face of the body 15 is formed with upwardly disposed teeth 16 and these may be formed in any number of ways such as by milling as shown in Figures 2 and 3 or by means of an added stamped plate 17 riveted at 18 to the leg as shown in Figure 4.

The second leg 14 has a body 19 and extends upwardly from its companion jaw 11 and is secured thereto by a relatively larger radius bend 20 which disposes the body slightly less than 90° from the jaw. The angle is not critical, however, and may be at right angle plus or minus if desired.

A lip 21 is formed on the free end of the body 19 and aligned apertures 22 and 23 are formed in the radius or bent portions of the legs 14. It

will be seen that the lower jaw and the body 19 are of greater width than the body 15 and therefore sufficient material is present to permit the apertures 22 and 23 to be large enough to receive the body 15 extending downwardly therethrough. Teeth 24 are formed on the body 19 of second leg 14 and communicate with apertures 22 and 23 and may thus mesh with teeth 16 of first leg 14. It is easily seen that the jaws may thus be secured in selective spaced relation by meshing the teeth of one leg with those of the other.

In the modified form of Fig. 5, the second leg 30 is also straight throughout its length and has a series of transverse teeth 31 adapted to mesh with the teeth 32 of the first leg which has a 15 longitudinally extending central slot 33 which is aligned with an internally threaded aperture 34 in leg 30 and a headed bolt 35 releasably secures the teeth in selective meshing engagement.

Having thus described my invention, I claim:

An adjustable Venetian blind clamp comprising cooperating spaced parallel jaw members for releasably securing the lower rail of a Venetian blind to the sill of the window frame from which the blind is hung; each said jaw being provided with padded faces disposed to contact the sill and rail; juxtaposed legs carried by the jaws at one end and disposed substantially at right angles thereto; one said leg being substantially longer than the other and having a plurality of 25 teeth disposed toward its jaw and on its inner side face; the other said leg being of a greater

5
10

width than the first described leg; a lip carried by the free end of said second leg and extending substantially in parallel relation to its jaw; said second leg having upper and lower apertures at its ends adjacent the lip and jaw respectively; a tooth in the lower aperture extending transversely at the supported end of its respective jaw; and said first leg extending downwardly through said upper and lower apertures with its teeth disposed to cooperate with said tooth, whereby spreading pressure on said jaws urges the teeth into locking engagement with said tooth.

JOHN M. MIKOSKI.
